CLAIM

We claim the ornamental design for a centrifuge clip, as shown and described.

DESCRIPTION

FIG. 1 is a bottom perspective view of a centrifuge clip of the new design, wherein the clip is shown in an open position; FIG. 2 is a bottom perspective view of the centrifuge clip of FIG. 1, wherein the clip is shown in a closed position; FIG. 3 is a top view of the centrifuge clip of FIG. 1; FIG. 4 is a left side view of the centrifuge clip of FIG. 1; FIG. 5 is a bottom view of the centrifuge clip of FIG. 1; FIG. 6 is a right side view of the centrifuge clip of FIG. 1; FIG. 7 is a front view of the centrifuge clip of FIG. 1; and, FIG. 8 is a rear view of the centrifuge clip of FIG. 1. The portions of the Figures shown in broken lines are for illustrative purpose only and form no part of the claimed design.
